Primary Examiner — Joshua Kading*Assistant Examiner* — Sharon H Schwartz(74) Attorney, Agent, or Firm — Banner & Witcoff, Ltd.(57) CLAIM

The ornamental design for a shoe, as shown and described.

DESCRIPTION

FIG. 1 is a bottom view of a shoe showing my new design; FIG. 2 is a bottom rear perspective view thereof; and, FIG. 3 is a bottom front perspective view thereof.

The broken line adjacent to the solid line and unshaded area therein depicting the internal portion of the shoe sole element forms no part of the claimed design. The broken lines and unshaded areas depicting the remainder of the shoe form no part of the claimed design.

1 Claim, 3 Drawing Sheets(56)
